AIR CONDITIONING DEVICE

August Young, Flushing, N. Y.

Application August 5, 1932. Serial No. 627,643

12 Claims. (Cl. 257—8)

This invention relates to apparatus and system for conditioning air in the room of a house, in railway cars or steamship compartments, buses or other enclosures.

5 The invention broadly aims to provide an apparatus by virtue of which a room or other enclosure is properly and uniformly cooled or heated and at the same time ventilated independently of or without the necessity of opening the doors 10 or windows.

More particularly, the invention comprehends an apparatus which includes means for conveying and uniformly distributing throughout a room or equivalent enclosure, a supply of fresh heated or 15 cooled air, together with means for receiving and conveying away foul air, so that constant circulation of the air in the room is insured.

As a further feature, the invention embodies the idea of employing the means of conveying 20 and distributing the fresh air, as a means for humidifying the air supply when heated and for conveying off condensation, when the air supply is cooled.

The invention further resides in the provision 25 of an air conditioning apparatus or system of the indicated character which is comparatively simple in its construction and mode of operation, inexpensive to produce, install and maintain in working condition, and which is highly 30 efficient in its purpose.

With the above recited and other objects in view, reference is made to the following specification and accompanying drawings, in which there is illustrated several preferred embodiments of 35 the invention, while the claims define the actual scope thereof.

In the drawings:

Figure 1 is a fragmentary horizontal sectional view of an air conditioning apparatus constructed 40 in accordance with the invention and illustrating the same installed in a room or equivalent enclosure.

Figure 2 is an enlarged fragmentary sectional perspective view of one corner of the apparatus.

45 Figure 3 is a vertical sectional view diagrammatically illustrating the apparatus.

Figure 4 is a plan view with parts shown in section illustrating the apparatus as applied to a railway car or other vehicle.

50 Referring to the drawings by characters of reference, the apparatus includes a hollow molding designated generally by the reference character A which is designed to be applied to the wall of the enclosure at a point spaced below the ceiling.

55 The molding A includes a rear wall 5, a front wall

6 which may be variously contoured to lend thereto the desired ornamental, a bottom wall 7 and a top wall 8. The molding is sub-divided into upper and lower ducts 9 and 10 by horizontal partition 11 and the upper wall 8 is formed with 60 a series of inlet openings 12 communicating with the duct 9 and designed to receive therethrough foul air which is drawn off from the duct 9 by one or more pipes or conduits 13 which communicate with the inlet of an exhaust pump or fan 14. 65 The front wall 6 is formed with a plurality of openings 15 for discharging fresh air from the duct 10, which air is supplied thereto through a pipe or conduit 16 leading from the outlet 17 of a fan or blower 18 which draws in fresh air 70 from outside of the enclosure. The fresh air duct 10 has extending therethrough a conduit or pipe 19 which leads to and may be optionally connected with a refrigerator unit 20 or a heating unit 21 depending upon whether the air supply 75 is to be cooled or heated. As illustrated, the conduits or pipes 22 lead from the conduit or pipe 19 and are provided with branches 23 and 24, the former leading through the refrigerator unit 20 and the latter through the heating unit 21. 80 Valves 25 and 26 control the optional establishment of communication of the conduit or pipe 19 with the refrigerating and heating units.

When the apparatus is employed for supplying a cooled fresh air supply to the room or enclosure, 85 the lower portion of the molding A serves as a trough T for the reception of condensation which forms on the exterior of the pipe or conduit 19. When the apparatus is employed to supply heated fresh air to the room or enclosure, the lower portion of the molding A provides a trough T for water for moistening or humidifying the heated air discharged or supplied to the room or enclosure. In order to optionally convey off the condensation from the trough T or supply water for humidifying 90 the heated air, a pipe or conduit 27 communicates with the lower trough-forming portion of the molding A and leads therefrom to branch pipes 28 and 29 connected respectively with a drain 30 and a water supply 31, valves 32 and 33 95 being provided in said branches for selectively cutting off or establishing communication between said branches and the pipe 27.

In order to strengthen the molding at the corners of the room or enclosure, corner pieces, such 105 as castings 35, are located within the lower compartment 10 and snugly fit the compartment. The corner pieces 35 in addition to strengthening and re-inforcing the structure of the molding at the corners also serve as unions for connecting 110

and establishing communication between the sections of the conduits or pipes 19. This is accomplished by providing the corner pieces with a passage 36 into which the extremities of adjacent 5 pipe sections 19 are threaded. In order to permit the condensation or humidifying water to flow past the corner pieces, the lower edge thereof is grooved as at 37.

Where the apparatus or system is applied to a 10 vehicle, advantage may be taken of the motion of the vehicle to promote circulation for the purpose of supplying fresh air and expelling foul air. This is illustrated diagrammatically in Figure 4 of the drawings wherein the lower duct 10 of the 15 molding A is provided with a forwardly directed inlet 40 which by virtue of the forward movement of the vehicle causes the fresh air to flow through the duct 10 and to be introduced and distributed throughout the vehicle enclosure. Also in this 20 arrangement the upper duct 9 is provided with a rearwardly disposed outlet 41 which by virtue of the forward movement of the vehicle induces a suction in the outlet for drawing off the foul air through the duct inlets 12.

25 It should be noted that in connection with the foul air duct 9 and the fresh air duct 10, the inlet openings 12 of the former and the outlet openings 15 of the latter may be of graduated size in accordance with their proximity to the outlet 30 of the former and the intake of the latter so as to insure uniform action.

While there has been illustrated and described several preferred embodiments or uses of the invention, it is to be understood this is merely illustrative of certain forms of the invention and is 35 not intended as a limitation upon the scope of the claims.

What is claimed is:—

40 1. An apparatus for conditioning the air in a room including means extending around the walls of the room, said means defining continuous independent ducts for receiving and conveying away the foul air and for receiving and discharging fresh air into the room, and a conduit extending throughout the latter duct for affecting the temperature of the fresh air supplied to the room from said latter duct.

45 2. An apparatus for conditioning the air in a room including means extending around the walls of the room, said means defining continuous independent ducts for receiving and conveying away the foul air and for receiving and discharging fresh air into the room, and a conduit extending throughout the latter duct for affecting the 50 temperature of the fresh air supplied to the room from said latter duct, said duct also serving as a condensate receptacle or as a container for a humidifying fluid.

60 3. An apparatus for conditioning the air in a room including a hollow molding extending around the walls of the room adjacent the ceiling, a horizontal partition in said molding dividing the same into upper and lower continuous ducts for respectively receiving and conveying 65 away from the room the foul air through the upper duct and for receiving fresh air, conditioning the same within said lower duct and discharging said fresh conditioned air to the room from said lower duct, and means respectively connected 70 with said ducts for creating a suction to exhaust the foul air from the upper duct and for drawing fresh air into the latter duct and discharging said fresh conditioned air therefrom into the room.

75 4. An apparatus of the character set forth including a member extending around the side walls

of an enclosure adjacent the top wall thereof, said member defining continuous independent upper and lower ducts, each having throughout their lengths communication with the interior of the room at different levels, means connected with the upper duct for creating a suction therein to withdraw from the enclosure through said duct the foul air and means connected with the lower duct for drawing in fresh air from the outside of the enclosure and for discharging through said lower duct fresh air into the enclosure, a continuous conduit extending through the lower duct, a refrigerating unit, a heating unit, and means for optionally connecting the conduit with either unit to selectively heat or cool the fresh air supplied to the room.

80 5. An apparatus of the character set forth including a member extending around the side walls of an enclosure adjacent the top wall thereof, said member defining continuous independent upper and lower ducts, each having throughout their lengths communication with the interior of the room at different levels, means connected with the upper duct for creating a suction therein to withdraw from the enclosure through said duct the foul air and means connected with the lower duct for drawing in fresh air from the outside of the enclosure and for discharging through said lower duct fresh air into the enclosure, a continuous conduit extending through the lower duct, a refrigerating unit, a heating unit, and means for 85 optionally connecting the conduit with either unit to selectively heat or cool the fresh air supplied to the room, the lower portion of the lower duct selectively serving as a container for a humidifying liquid when the air is heated and as a condensation receiver when the air is cooled.

90 6. An apparatus for conditioning the air in a room including a hollow molding extending around the walls of the room adjacent the ceiling, a horizontal partition in said molding dividing the same into upper and lower continuous ducts for receiving and conveying away from the room the foul air and a lower duct for receiving and supplying fresh air to the room, a continuous conduit extending through the lower duct for affecting the temperature of the fresh air supplied to the room, and corner pieces located within the lower duct at the corners thereof having a passage therethrough for uniting and establishing communication between the conduit sections.

95 7. An apparatus for conditioning the air in a room including a hollow molding extending around the walls of the room adjacent the ceiling, a horizontal partition in said molding dividing the same into upper and lower continuous ducts for receiving and conveying away from the room the foul air and a lower duct for receiving and supplying fresh air to the room, a continuous conduit extending through the lower duct for affecting the temperature of the fresh air supplied to the room, and corner pieces located within the lower duct at the corners thereof having a passage therethrough for uniting and establishing communication between the conduit sections, said corner pieces having grooved lower faces establishing communication between the portions of the lower duct located on opposite sides of the corner pieces.

100 8. A hollow molding for conditioning the air in a room, said molding including a body subdivided to define independent superposed and subterposed ducts, each having communication with the room, means connected with the superposed

- duct for inducing a suction therein to draw off the foul air therethrough, means connected with the subterposed duct for supplying therethrough to the room fresh air from the exterior of the room, and means extending through the subterposed duct for affecting the temperature of the fresh air prior to its expulsion from the duct into the room. 80
9. A hollow molding for conditioning the air in a room, said molding including a body subdivided to define independent superposed and subterposed ducts, each having communication with the room, means connected with the superposed duct for inducing a suction therein to draw off the foul air therethrough, means connected with the subterposed duct for supplying therethrough to the room fresh air from the exterior of the room, means extending through the subterposed duct for heating the fresh air prior to its introduction to the room, and means for supplying water to the lower duct for humidifying the heated fresh air supply. 85
10. A hollow molding for conditioning the air in a room, said molding including a body subdivided to define independent superposed and subterposed ducts, each having communication with the room, means connected with the superposed duct for inducing a suction therein to draw off the foul air therethrough, and means 90

11. A hollow molding for conditioning the air in a room, said molding including a body subdivided to define independent superposed and subterposed ducts, each having communication with the room, means connected with the superposed duct for inducing a suction therein to draw off the foul air therethrough, means extending through the subterposed duct for cooling the fresh air prior to its introduction to the room, and for dehumidifying the cooled fresh air prior to its introduction to the room. 100
12. In an apparatus for ventilating an enclosure and for distributing and conditioning fresh air adjacent the points of distribution of the same to the enclosure, said apparatus including independent ducts extending around the walls of the enclosure, one duct for receiving and conveying away from the enclosure the foul air, the other duct for receiving and distributing fresh air around the enclosure and fresh air conditioning means extending around the walls of the enclosure and so located with reference to the fresh air duct as to condition the fresh air adjacent the points of its distribution and as it is distributed. 105
